HYDRAULIC FUSE

Robert L. Lavender, Cleveland, Ohio, assignor to
 The Marquette Metal Products Company,
 Cleveland, Ohio, a corporation of Ohio

Application September 19, 1942, Serial No. 459,051

3 Claims. (Cl. 251—114)

This invention relates to a device for safeguarding and/or preventing fouling of hydraulic machinery and apparatus or parts thereof in the event of accidental release of pressure in a hydraulically operated instrument or in the feed line of such instrument. The device is analogous in operation to an electric service line fuse and, for convenience, it will be referred to herein as a hydraulic fuse. The above indicates the general object.

The objects further include the provision of a hydraulic fuse which is compact and simple in construction; easy to build and install; capable of functioning properly in any mounted position; unlikely to fail to operate when the occasion requires operation, and which will be positive in action in a manner to block a hydraulic feed line upon the occurrence of sudden surge in the line or critical reduction of normal back pressure or flow resistance therein.

A special object is to provide a positively acting hydraulic fuse which can be reconditioned quickly for further service after it acts to block a hydraulic feed line; and a further object is to provide a hydraulic fuse in which the releasing element which causes the line to become blocked is an inexpensive filament or rod which is pulled apart and is easily accessible for replacement after the cause of breakage has been ascertained and remedied.

I am aware of the fact that spring operated devices have been proposed to safeguard hydraulically operated apparatus against line breakage, suddenly occurring leaks etc.; and that a device employing a frangible plate which requires sufficient release of force to shatter it are already known in the art. The spring operated devices are impositive in operation and sometimes reset themselves before the cause of the trouble has been ascertained; and the frangible plate arrangements require so much force to break them that they cannot serve the essential purpose in actual practice because a force which, to be effective must be released because of fracture due to compression beyond the intended limit may vary over a wide range. If, on the other hand, the fracturable element is subject to tension (pulled apart) in order to cause functioning at the critical time, said element can be made with much less expense and can be made capable of responding to a much more delicate safety limit in respect to the apparatus to be safeguarded thereby. Furthermore, a device which acts consequent upon release of prede-

terminable tension can more readily be replaced and can be operated to stop all flow in a hydraulic supply line without requiring any special reception pocket for the fractured parts.

In the accompanying drawing Fig. 1 is a side elevation of one form of hydraulic fuse; Fig. 2 is a plan view thereof; Fig. 3 is a sectional view as indicated at 3—3 on Fig. 2; Fig. 4 is a sectional view taken in two planes, substantially as indicated by the line 4—4 on Fig. 3, and Fig. 5 is a perspective view of one form of breakable or fracturable element of the device hereof.

Figs. 1, 2 and 3 show a hollow body 1 of generally cylindrical form having a threaded inlet portion 2 and similar outlet portion 3 adapted for receiving complementarily threaded portions 4 and 5, respectively, of piping or tubing leading from a source of supply to a hydraulically operated instrument to be safeguarded etc. as outlined above. A detachable cover plate 6 closes one side of the body, being secured thereto as by a series of screws 7, or, optionally—for enabling more rapid detachment of the plate if desired—a single screw may be employed at the center of the plate.

If a single screw or fastener is used then the joint surfaces between the cover plate and body would ordinarily require more elaborate sealing means to prevent leakage (e. g. require a compressible gasket of suitable form, not shown).

In Fig. 3 a central inlet orifice 9 opens into a relatively enlarged cylindrical valve chamber 10; and the hydraulic fluid can normally flow freely to the outlet orifice 11 shown aligned with the inlet, past peripheral surfaces of a check valve plate 12, as around the sides, top and bottom of the plate (see Fig. 4).

The valve plate 12 is preferably of curved or crescent shape, as shown; is, in effect, pivoted to the body on a supporting pin 13 and is retained, normally, in the position in which shown in Fig. 3 by an elongated, breakable tension element 15, supported in part by the valve plate and in part by a pin or post 16 fixed inside the body 1 parallel to the pivot pin 13.

The breakable or readily frangible element 15, as shown, is a rod, pin or filament of relatively small cross section with a knob 17 on each end. The breakable rod 15, adjacent one knob thereof, lies in an open-ended slot 18 at the end of the valve plate which lies remote of the pivot pin 13, and, adjacent the other knob, lies in an open-ended slot 19 in the pin or post 16 (open at the left end Fig. 4). As shown in Fig. 4, the slots

18 and 19 are at right angles to each other, said arrangement of slots maintaining the breakable rod in valve-plate-retaining position irrespective of the position in which the hydraulic fuse happens to be placed, and also, as will be explained presently, enabling the breakable element to be removed and replaced readily after breakage thereof occurs.

The breaking point of the element 15 in case it is a rod may be predetermined, if desired, by notching the rod as at 20, Fig. 5.

The retaining post 16 is fixed at one end to the rear wall of the body 1 (as by a press fit in the hole 21) and the opposite open-slotted end of the retaining post, as shown in Fig. 4, readily slides into a socket 22 in the cover plate. The pivot pin 13 is attached to the cover plate at one end (as by a press fit in opening 23), and the opposite end enters a pilot socket 24 in the rear wall of the body 1.

Preferably the pivot pin 13 has an enlarged shoulder portion 25 beyond the valve plate 12 in order that the valve plate will necessarily be removed from operating position when the cover plate is detached from the body. Removal of the cover plate, after the element 15 breaks, carries one end of the element 15 out of the body 1, along with the valve plate. The other end of the breakable element can then be removed easily, without requiring a special tool from the slot in the retainer post 16, as will be obvious from Fig. 4.

To replace the broken element 15, one end of a new element 15 is placed in the open slot 18 of the valve plate and the other end of the element is then slid into the open slot 19 of the retainer post 16 as the cover and valve plate assembly is returned to original position.

Special by-passage spaces of adequate projected area may be formed by centrally recessing the body and cover plate as at 26 and 27 respectively (counterbore effects). The circular margins radially outwardly beyond the recesses (28 and 29) constitute guiding lands for the valve plate end or side portions as will be evident from Figs. 3 and 4. The total area of by-passage at the margins of the valve plate are exaggerated in Fig. 4 for illustrative purposes. The total by-passage area around the valve plate 12, is, of course, determined by the sizes of the fluid inlet and outlet passages 9 and 11; and said total area should not be materially greater than either, or at least not materially greater than the area of the outlet.

The convex face of the valve plate 12 has a socket arranged to receive and support a sealing insert or plug 30 (e. g. cylindrical) of suitable resilient but wear-resisting material—for example, synthetic rubber in case the fluid handled by the hydraulic system is hydrocarbon; and the plug 30 is so positioned as to be swung by the plate into sealing relation to the outlet passage 11 whenever a sudden surge of predetermined

magnitude in the supply line causes the breakable element 15 to be pulled apart. Such sudden surge in the supply line is ordinarily caused by absence of the usual back pressure or resistance to free flow on part of the apparatus supplied with hydraulic fluid through the line in which the hydraulic fuse hereof is included. That causes the stream of fluid from the inlet 9 to be projected forcibly against the dished or indented rear side 31 of the valve plate (turbine jet and blade effect) so that, even if the by-passage spaces around the valve plate 12 are slightly larger in total projected area than the inlet or outlet opening areas, the device will function as described above when the normal resistance to flow beyond the outlet 11 fails to obtain.

I claim:

1. A hydraulic fuse comprising a hollow body having an inlet, an outlet and an enlarged chamber therebetween, a movable valve member in the chamber adapted to seal the outlet, means supporting the member for movement from unsealing position to sealing position, a slot in the valve member extending in a direction transverse to the direction of movement of the valve member, a double headed, elongated breakable holding element detachably occupying the slot with one head abutting the valve member adjacent the slot thereof, a retainer having a slot for detachably receiving another portion of the holding element and having a surface adjacent said slot for abutting the other head, said slots extending transversely of each other in a manner to prevent accidental detachment of the holding element from the valve member and retainer irrespective of the position in which the fuse is mounted.

2. The arrangement according to claim 1 wherein the valve member is pivotally mounted on a cover plate of the hollow body and its slot is an open ended slot for the breakable holding element, and the retainer is a pin rigid with the hollow body inside thereof and projecting toward the cover plate, the slot of the retainer pin extending lengthwise of the pin and being open at the end of the pin which lies adjacent the cover plate.

3. A hydraulic fuse comprising a hollow body with a generally cylindrical chamber therein, a detachable cover plate constituting one end wall of the chamber, inlet and outlet passages for fluid in the body disposed substantially diametrically of the chamber, a valve plate having sealing means for the outlet, a pivot pin on the cover plate parallel to the axis of the chamber and constituting a mounting for the valve plate by which the valve plate is removable from the chamber when the cover plate is detached, a post carried by the end wall of the chamber opposite the cover plate, and breakable means readily associative with the valve plate and post when the cover plate is moved to chamber closing position.
